UNITED STATES PATENT OFFICE.

WILLIAM E. BURCKY, OF CHICAGO, ILLINOIS.

LAMP.

1,091,118.

Specification of Letters Patent. Patented Mar. 24, 1914.

Application filed August 14, 1913. Serial No. 784,744.

To all whom it may concern:

Be it known that I, WILLIAM E. BURCKY, a citizen of the United States, residing at Chicago, in the county of Cook and State 5 of Illinois, have invented a new and useful Improvement in Lamps, of which the following is a specification.

My invention relates to an improvement in the class of lamps used as signals on vehicles; and it relates, more particularly, to an improvement in the glass face of such a lamp through which the light-rays are projected.

I have more immediately devised my improvement for use in automobile lamps, having been primarily induced thereto because of city-ordinances requiring modification of the light they throw, which is so intense as to be blinding with the resultant tendency 20 to cause accidents.

In the accompanying drawing, Figure 1 is a broken view of a lamp-body provided with my improved face shown in vertical section, and Fig. 2 shows the face in elevation.

25 The lamp-face 3 is made of glass, preferably by molding it in the disk-form illustrated, or of other suitable contour to fit its holder 4 on a lamp 5, the holder shown being a hinged annular head on the lamp, 30 which, in the present case, may be an automobile-lamp of ordinary or any suitable construction.

The face is provided with one flat side, which may be the inner one, as shown; and 35 the opposite, or outer side is formed with a series of transversely-extending ridges having downwardly-inclined upper surfaces 6 and horizontal, or approximately horizontal, lower surfaces 7. The glass forming the 40 face 3 is transparent, as a whole, but the surfaces 6 are rendered translucent in any suitable way. This may be done by darkening or coating them with a translucent paint, shellac or varnish, or by grinding or frosting them, or otherwise.

45 With a light (not shown) burning in the lamp 5, the rays passing through the translucent surfaces 6 are greatly modified in intensity, and present a comparatively mild 50 degree of illumination; and these surfaces reflect a portion of the light through the transparent surfaces 7 and direct them

downwardly toward the ground to illuminate the latter without producing the objectionable blinding effect of the light referred to.

My improved glass lamp face may be used in a lamp 5, when desired, with its ridged surface innermost and its opposite surface outermost, thus in a position the reverse of that illustrated in Fig. 2.

While my improvement is shown as the glass covering-face of a lamp-body, it is within my invention to provide it in any form for covering or shielding the light-rays passing through the face of a lamp-body.

What I claim as new and desire to secure by Letters Patent is—

1. A glass lamp-face covered on one side with a series of ridges of angular cross-section formed with downwardly-inclined translucent outer surfaces and lower transparent surfaces extending at an angle to said inclined surfaces, for the purpose set forth.

2. A lamp-face comprising a body of transparent glass covered on one side with a series of ridges of angular cross-section formed with downwardly-inclined translucent outer surfaces and lower transparent horizontally-extending surfaces, for the purpose set forth.

3. A lamp-face comprising a body of transparent glass provided on one side with a series of ridges of angular cross-section formed with downwardly-inclined outer surfaces coated with translucent material and lower transparent surfaces extending at an angle to said inclined surfaces, said translucent surfaces adapted to act on and diffuse the rays striking normal to the other side of said lamp-face.

4. A glass lamp having on one side a plurality of ridges, a portion of each ridge being transparent and the remaining portion being translucent, the translucent portions covering the entire surface acted upon by rays normal to the other side of said lamp-face.

WILLIAM E. BURCKY.
